EXPANSIBLE TOOL FOR REMOVING
LAMP BASESJack Shapiro and Marvin Shapiro,
New York, N. Y.

Application May 11, 1946, Serial No. 669,061

5 Claims. (Cl. 81—72)

1

This invention relates to tools for removing lamp bases from their sockets.

The primary object of the present invention is the provision of a tool which is particularly well adapted for use in removing lamp bases from sockets from which it is difficult to remove the lamp bases, which is frequently the case, especially in outdoor electric light signs due to corrosion of the lamp bases in the sockets, or due to paint or other causes.

Another object of the invention is to provide a lamp base removing tool which is well adapted to remove the lamp base from the socket by unscrewing the base from the socket, and which is of such construction and operation as to facilitate the removal of the lamp base from the tool after the lamp base is removed from the socket.

A further object is generally to provide a lamp base removing tool which is of simple construction and which is highly effective for its purposes and easy to use.

Another object is the provision of a tool for cleaning the inner surfaces of electric light sockets.

The above and other objects, features and advantages of the present invention will be fully understood from the following description considered in connection with the accompanying illustrative drawings.

In the drawings:

Fig. 1 is a side view of a lamp base removing tool embodying the present invention;

Fig. 2 is a view similar to Fig. 1 showing the tool carrying a lamp base which has been removed from a socket;

Fig. 3 is a view of the tool partly in elevation and partly in section, the positions of relatively movable parts of the tool corresponding to the positions shown in Fig. 1.

Fig. 4 is an end view of the tool.

Referring now to the drawings, in detail, the tool 10 embodying the present invention comprises a lamp base gripping member 12 and an operating member 14 for conditioning the gripping member 12 to grip and release the lamp base and for actuating the gripping member for removing the lamp base from the socket.

The gripping member 12 is preferably formed of spring steel and comprises a part 16 which is preferably cylindrical and which is internally screw-threaded as indicated at 18. Gripping member 12 is radially expansible and contractable and for this purpose is provided with a plurality of circumferentially spaced longitudinal slots 20 which extend to the free outer end of said

gripping member forming a plurality of resilient segments 22 which extend longitudinally of the gripping member. It will be understood that the gripping member 12 is peripherally continuous except in the slotted portion which provides the resilient segments 22. The outer end portion of gripping member 12 is externally screw-threaded as indicated at 24 to fit the internal screw-threaded surface of a lamp base which is indicated at 10 B in Fig. 2. It will be understood that screw-threaded portion 24 of the gripping member is cylindrical and that in its normal or contracted condition it may be inserted within or threaded into the screw-threaded shell of the lamp base after a sufficient amount of the glass of the lamp bulb and the material which was used for securing the lamp bulb in the base have been removed. Preferably, but not necessarily, the diameter of threaded portion 24, in its normal contracted condition, is such that it is insertable into the base only by screwing it into the lamp base. A shoulder 26 is provided on the gripping member to limit the extent of insertion of part 24 of the gripping member in the lamp base.

26. The operating member 14 comprises a rigid stem or spindle 28 having a threaded portion 18 which is in screw-threaded engagement with the threaded portion 30 of the lamp base gripping member 12. Said stem 28 has an outwardly flaring or inwardly tapering outer end portion 32 which is of circular cross section and which is in engagement with the outwardly flaring inner surface 34 of the outer end portion 24 of the gripping member so that as a result of relative rotation of members 12 and 14 in a predetermined direction end portion 32 of operating member 14 moves axially or longitudinally inwardly of the outer end portion 24 of gripping member 12 thereby radially expanding the latter for securely gripping the lamp base B internally thereof, with the raised screw portions of part 24 in the grooves of the screw-threads of the lamp base internally thereof. It will be understood that parts 24 and 32 are concentric or coaxial.

40. Provision is made for releasably holding members 12 and 14 against relative rotation. For that purpose, a locking member 36 which as here shown is in the form of a sleeve has a sliding fit on spindle 14 but is held against rotary movement thereon by a pin 38 which is fixed to said spindle and which projects into a slot 40 provided in said locking member. The adjacent end of gripping member 12 is provided with one or more notches 42 in which a companion integral projection 44 of locking member 36 has a removable fit, in one

position of said locking member longitudinally of spindle 28 for releasably preventing relative rotation between gripping member 12 and operating member 14. A spring pressed ball 46 is disposed within a lateral groove 48 in spindle 28 and is engageable in either of two recesses 50 and 52, respectively, for releasably holding the locking member in its locking and retracted positions, respectively. A rigid pin 54 is fixed to spindle 14 and projects laterally thereof for engagement with the adjacent edge 56 of part 16 of the gripping member 12 for limiting the movement of spindle 28 longitudinally toward the outer split end of member 12. It will be understood that when pin 54 is in engagement with edge 56 of part 16 of member 12, the lamp base gripping member is in its normal or radially contracted condition. Spindle 28 is provided with a cross pin or handle 58 for actuating the tool and for use in effecting the relative rotation of members 12 and 14.

Figs. 1 and 3 show relative positions of the parts of the tool in which the threaded part 24 of the tool is insertable into the lamp base B, the screw-threaded portion 24 of the tool being radially contracted. The screw-threaded shell or socket in which the lamp base is mounted and from which it is to be removed by the tool is not shown since sockets of this type are well known.

The lamp base being in its socket is removed therefrom in the following way: The threaded end portion 24 of the tool, being constructed so that it can be threaded into the base internally thereof is rotated by operation of the spindle 14 by means of the handle 58, the locking member 36 being in its locking position as shown in Fig. 1. This is effected by turning the tool in the direction of arrow A in Fig. 1, preferably through about three revolutions. Then the locking member 36 is released from the gripping member 12, as illustrated in Fig. 2 and member 14 is then rotated in the opposite direction as indicated by the arrow B in Fig. 2. The rotation of member 14 in this last mentioned direction results in the radial expansion of screw-threaded portion 24 of the outer gripping member so that the latter securely grips the lamp base internally thereof whereby continued operation thereafter of the tool in the same direction is effective to unscrew the lamp base from the socket for removing the lamp base therefrom.

After the lamp base is removed from its socket, spindle 28 of operating member 14 is turned in the opposite direction, say in the direction of arrow A in Fig. 1 while the gripping member 12 is held against rotation, for example, by holding the lamp base B which is mounted on said gripping member, until the radial pressure of the screw-threaded portion 24 on the internal screw-threaded surface of the lamp base is released. Then the locking member 36 is returned to its locking position to prevent relative rotation of members 12 and 14 so that removal of the lamp base B from the tool is facilitated by unscrewing said lamp base from the threaded portion 24 of the tool. In case more than average difficulty is encountered in removing the lamp base from its socket by turning the handle 28 by hand, a wrench or other suitable tool may be applied to member 12, and for this purpose portion 16 of said member is provided with a hexagonal or other part 60 which may be engaged by a wrench and thereby rotated. The outer end of spindle 28 is preferably recessed as indicated at 62 in Fig. 3 to receive parts of the lamp or lamp securing material

which might not have been removed from the lamp base preliminary to the insertion of the tool in the lamp base as referred to above.

The tool of the present invention can be used for cleaning electric lamp sockets as well as for removing lamp bases therefrom. In this connection, it will be understood that the tool may be inserted in the socket so as to engage the threaded portion 24 of the tool with the screw-threaded shell of the socket internally thereof. The portion 24 may be expanded, if desired, to provide the required fit between the outer surface of said portion and the inner threaded surface of the socket shell so that rotation of the tool results in scraping and cleaning the said surface of the socket. Thus the tool is particularly well adapted for removing paint, corrosion and other foreign material from the inner surface of the socket shell whereby to clean the same and thereby improve the electrical conducting condition thereof.

It will be understood that various changes in the details of construction and in the arrangement of parts may be made without departing from the underlying idea or principles of our invention within the scope of the appended claims.

Having thus described our invention, what we claim and desire to secure by Letters Patent is:

1. A tool for removing a lamp base from a socket comprising a cylindrical member having an outer end portion adapted to grip said base internally thereof and provided with a plurality of circumferentially-spaced longitudinal slits defining segmental portions whereby said end portion is radially expansible and contractable, said member having an internally screw-threaded portion spaced axially of said outer end portion, and an operating member disposed axially of said cylindrical member, said operating member having rotating means integral therewith and being provided with a threaded portion in rotary engagement with said internally screw-threaded portion of said cylindrical member and with a flared end portion adjacent the inner surfaces of said segmental portions, said last mentioned portion of said operating member being operable to expand said segmental portions of said cylindrical member into secure gripping relation with said base when said operating member is rotated in a predetermined direction in relation to said cylinder, and releasable means for preventing relative rotation of said gripping member and said operating member, said releasable means comprising a locking member movable longitudinally of one of said members, means engaging said releasable means and said one of said members to prevent rotation of said releasable means on said one of said members, the other of said members having a recess and said locking member being engageable with the other of said members in said recess for preventing turning thereof and being retractable by longitudinal movement out of engagement with said other member, and resilient locking means internally of said operating member engageable with said locking member for holding said locking member in locked or retracted condition.

2. A tool for removing a screw threaded lamp base from a threaded socket, comprising a member having an internally screw-threaded part, a plurality of circumferentially disposed segments carried by said member at one end thereof, said segments being radially movable from retracted positions to expanded positions for gripping the lamp base internally thereof, said segments having inner surface portions which flare outwardly

toward the outer ends of the segments, a rod having rotating means integral therewith and having a screw threaded stem which is in screw-threaded engagement with said member internally thereof in engagement with said screw-threaded part, and an inwardly tapering part carried by said rod at one end thereof in juxtaposition to said outwardly flaring surface portions of said segments whereby rotation of said rod in relation to said member in a direction for unscrewing the lamp base from its socket results in axial movement of said part toward the opposite end of said member and in radial outward movement of said segment to clamp the latter radially against the lamp base, so that continued rotation of said rod in said direction causes the lamp base to be unscrewed from its socket, and means for releasably holding said member and said rod against relative rotation comprising a sleeve slidable on said rod, means engaging said sleeve and rod preventing relative rotation of said sleeve and rod, interengaging means on said sleeve and said member preventing relative rotation of said sleeve and said member, and resilient locking means internally said rod and engageable with said sleeve for holding said sleeve in locked or retracted condition.

3. In a tool for removing a screw threaded lamp base from a threaded socket, said tool having a gripping member and an operating member in coaxial disposition, said operating member being rotatable within said gripping member; clutch means for engaging and disengaging said members comprising a sleeve slidable on said operating member, means engaging said sleeve and said operating member for preventing relative rotation of said sleeve and operating member, interengaging means on said sleeve and said gripping member preventing relative rotation of said sleeve and said gripping member, and resilient locking means for holding said sleeve in engaged or disengaged condition.

4. In a tool for removing a screw threaded lamp base from a threaded socket, said tool having a gripping member and an operating member in coaxial disposition, said operating member being rotatable within said gripping member; clutch means for engaging and disengaging said members comprising a sleeve slidable on said operat-

ing member, means engaging said sleeve and said operating member for preventing relative rotation of said sleeve and operating member, interengaging means on said sleeve and said gripping member preventing relative rotation of said sleeve and said gripping member, and resilient locking means internally said operating member and engageable with said sleeve for holding said sleeve in engaged or disengaged condition.

- 10 5. In a tool for removing a screw threaded lamp base from a threaded socket, said tool having a gripping member and an operating member in coaxial disposition, said operating member being rotatable within said gripping member; clutch means for engaging and disengaging said members comprising a sleeve slidable on said operating member, means engaging said sleeve and said operating member for preventing relative rotation of said sleeve and operating member, interengaging means on said sleeve and said gripping member preventing relative rotation of said sleeve and said gripping member, and resilient locking means comprising a spring pressed ball disposed within a lateral groove in said operating member, said sleeve being provided with recesses on its internal surface for receiving said ball whereby said sleeve is retained in engaged or in disengaged position.
